UNITED STATES PATENT OFFICE

TAYLOR W. ROSS, OF MADISON, INDIANA, ASSIGNOR TO THOMAS GRAHAM & CO., INC.,
OF MADISON, INDIANA, A CORPORATION OF INDIANA

PORCH SWING

Application filed May 26, 1928. Serial No. 280,820.

The object of my invention is to produce a cheap porch swing of knock-down type of such character that the various elements may be so assembled for shipment as to be capable of transportation by parcel post without crating or placement in a protective carton, whereby an exceedingly low-priced article may be placed before consumers, the construction being such that the parts may be 10 readily assembled by an average householder without the use of any tools other than a small wrench commonly found in every house-hold.

The accompanying drawings illustrate my 15 invention. Fig. 1 is a perspective view of my improved swing assembled ready for use, Fig. 2 is an end elevation of the parts as shown in Fig. 1, Fig. 3 is a bottom plan of the parts shown in Fig. 2, Fig. 4 a fragmentary front elevation, Fig. 5 a section, on a larger scale, on line 5—5 of Fig. 4, Fig. 6 a fragmentary vertical section showing the lower connection between the lower edge of the back and one of the arm posts, Fig. 7 a 20 fragmentary horizontal section through the horizontal clamping bolt shown in Fig. 6, Fig. 8 an end elevation of the parts in relationship, Fig. 9 a transverse section of the assembly shown in Fig. 8 and Fig. 10 a plan 25 of the assembly shown in Figs. 8 and 9, portions of the vertical slats of the back section having been broken away to disclose parts which would be otherwise hidden.

In the drawings A indicates the seat portion, B, B, the two arm portions and C the back section.

The seat portion comprises front and rear wood bars 20, 20 framed together with cross bars 21, 22 and 23, said cross bars supporting a series of longitudinal seat-forming slats 24, the whole forming the unitary structure A.

Each of the arm sections comprises a horizontal arm 30 and front and rear vertical posts 31 and 32 respectively, secured to the under side of the arm 30. Each of the posts 31 and 32 is provided in its outer vertical edge with a continuous groove 33 for the reception of an assembling and suspension bolt 34, and the arm 30 is perforated, in align-

ment with each groove 33, for the reception of said bolt. The front and rear bars 20 of the element A are also vertically perforated, as indicated in dotted lines 35 in Fig. 4, said perforation being accurately spaced 55 from the adjacent end of one of the slats 24 so that when a vertical post 31 is placed with its inner vertical edge against the end of said slat the perforation 35 will closely align with the groove 33, and post 31 will be 60 held tightly between bolt 34 and the end of said slat.

The horizontal width of arms 30 is preferably equal to, but not greater than, the vertical width of the bars 20 of frame A, and the length of posts 31 is such that the total vertical dimension of the arm section B is less than the distance between the adjacent faces of the two bars 20 of section A, and the length of the arms 30 is equal to the distance 65 between the adjacent faces of the two cross bars 22 and 23 less the thickness of one of posts 31, for a reason which will be made clear hereinafter.

The back section C is composed of upper 75 and lower horizontal bars 40 and 41 framed together with vertical end bars 42, 42, vertical slats 43 extending between the adjacent edges of bars 40 and 41, at spaced intervals, being held in position most convenient 80 by having their upper and lower ends inserted and retained in grooves 45 formed in the lower and upper edges of the bars 40 and 41 respectively.

Each bar 42, at a point intermediate its 85 ends, and somewhat closer to its lower end, is perforated to receive a clamp bolt 50 passed therethrough and through a perforation 51 formed through the tongue 52 which is formed at the outer rear corner of each of the 90 arms 30.

At each lower corner of the back section C the lower bar 41 and the lower ends of the end bars 42 are perforated at 55 (Fig. 6) and each rear arm post 31 is perforated at an 95 intermediate point, as indicated at 56, to receive the horizontal clamping bolt 57 (Fig. 6) which may be tightly held in place by nut 58.

The vertical dimension of the back element 100

C is preferably equal to but not greater than the front to rear outside dimension of the seat element A, and the length of bars 40 and 41 is preferably equal to, but not greater than, the length of bars 20.

Each of the bolts 34 is provided at its upper end with an eye 60 to receive one end of a suspension bridle 61, and the lower ends of these rods are threaded to receive nuts 62, washers 63 and 64 being preferably placed respectively under the eye and nut of the bolt so that the parts, when assembled in use condition, may be firmly clamped together.

I have found that, by constructing the swing in the manner described it is possible for me to use material of such dimensions that the parts would ordinarily be scraped in factories producing a regular line of wood products. I have also found that, by making the sections at B and C, as above described, of such dimensions that, when assembled for shipment, as shown in Figs. 8, 9 and 10, the overall dimension of the assembly may be within parcel post limits and, because of the relative proportions of the sections A, B and C such assembly may be made sufficiently rigid, by the use of ordinary bailing straps, the bundle will be acceptable for individual shipment without the need of crating, protective corrugated paper cartons, etc., and that consequently mail order houses may ship these packed units at a very low expense, much lower than could be done if crating or cartoning were necessary, and as a consequence the swing may be placed in the hands of the ultimate consumer at a much lower price than has heretofore been found to be possible.

In preparing the several elements for shipment the two arm elements B, B are nested between the cross bars 22 and 23 and the front and rear bars 20 of the frame A beneath the seat slats, as shown in Fig. 10, and in order to hold these elements against rattling, and at the same time to somewhat stiffen the seat slats between the two cross bars 22 and 23, I secure to the under side of the seat slats a cross bar 70, the length of which is equal to the distance between the adjacent faces of bars 20 less an amount equal to twice the thickness (vertical dimension) of the arms 30, the bar 70 having its ends equally spaced from the adjacent faces of bars 20. The arm sections B, B when packed for shipment, as shown in Fig. 10, may thus be securely held in place without the need of fastening members and back section C may be laid upon the under edges of bars 20, thus retaining the arm sections in place.

In order to form a pocket for the reception of the suspension chains, the four bolts 34, the two bolts 55, and the two bolts 51, together with their associate nuts and washers, I secure one or more thin strips 80 in the space between cross bars 21 and 22 of seat

section A beneath slats 24, as indicated in section in Fig. 9 and in fragmentary elevation in Figs. 3 and 10. By placing a sheet of reasonably heavy paper in the pocket 81 thus formed, so as to bridge the spaces between the slats 24, the bolts, with their nuts and washers, and the suspension chains may be readily packed in the pocket 81 for shipment, without special wrapping.

When the parts have been assembled as shown in Figs. 8, 9 and 10, they may be firmly strapped by two metal bailing straps around the bundle from side to side, rather than endwise, so that short bailing straps may be used, the various corners being protected against abrasion by the usual shipping pads placed under the bands, and if desired, either pads or a sheet of paper being placed between the seat section and the back section to prevent possible marring of the finished surfaces.

Upon receipt of a package composed as illustrated in Figs. 8, 9 and 10 the user may easily assemble the parts into use form, as indicated in Figs. 1 to 7 inclusive.

It will of course be understood that while I have described a porch swing constructed in accordance with my invention, the same principles of construction, whereby shipment by parcel post will be possible, may be adopted in the construction of other articles of furniture of the knockdown type. It will also be understood that in order to obtain the best results in shipment, the lengths of the top and bottom bars of the back frame should be equal to the lengths of the seat sills.

I claim as my invention:

1. An article of furniture comprising a seat section, a pair of arm sections having vertical posts detachably secured to the seat section substantially in the upper plane thereof, a back section, clamping means passing through said back section and through two of the arm section posts at an intermediate point in the lengths of said posts and transversely of the seat section, and clamping bolts passing through intermediate points in width of the back section at the ends thereof and through adjacent portions of the arm sections.

2. An article of furniture comprising a wood frame seat section consisting of side bars, connecting cross bars and seat slats; a wood frame back section consisting of upper and lower longitudinal bars, connecting end cross bars and intermediate back slats, the overall widths and lengths of said two sections being such that the back section may be placed upon the under side of the seat section without substantial relative projection; two arm sections each comprising a horizontal arm element and two supporting posts each of which is longitudinally grooved in its outer vertical edge, said arm sections being nestable between the side bars and cross

bars of the seat section beneath the seat slats without interfering with placement of the back section upon the under side of the seat section; and means for clamping the arm sections, upon the seat section, and the back section upon the arm sections, in use position, said clamping means comprising suspension bolts passing through the grooves of the arm posts and the side bars of the seat section and serving to clamp the arm frames firmly upon the seat section with the vertical posts of the arm sections firmly held between said bolts and adjacent ends of the seat slats.

In witness whereof, I have hereunto set my hand at Madison, Indiana, this 22nd day of May, A. D. one thousand nine hundred and twenty eight.
